CLOTHESLINE MANIPULATOR

Willis D. Waddell, Calgary, Alberta, Canada

Application April 1, 1946, Serial No. 658,812
In Canada May 15, 1945

5 Claims. (Cl. 211—119.13)

1

My invention relates to clothes line manipulators for the attachment and for the release of clothes and the like to and from a clothes line respectively, said clothes line being of special construction for this purpose, and the objects of this my invention are to provide a handy device through which a twisted two strand line may be pulled, and by such action the strands to become separated from one another adjacent to the device sufficiently so that portions of the articles to hang therefrom are securely gripped therebetween, to accomplish which a continued movement of the line by hand in a direction away from the device permits the strands to regain their twisted relationship to clamp the inserted clothes in a hanging manner, and conversely, by reversing the direction of movement of the line the clothes will automatically fall from between the strands of wire as they are drawn toward the device due to the separation of the strands as they enter and pass through the device.

An important advantage in my invention is that rotation of the wires about their common twisted axis is impossible when the device is rigidly attached to the holder provided on one of the lengths of wire employed with a supporting pulley as in the preferred type, thus avoiding any tangling of the clothes.

A further advantage is the speed and ease with which placing of the clothes on the line may be done, and the fact that the dried clothes will drop from the line, if so desired, without handling immediately the strands of the double wire spread from one another as the line comes to within a few inches of this strand parting device.

A still further advantage is that clothes pins are not needed in my invention, since the twisted strands of wire grip the articles between them in a positively secure manner until separated by moving the wire through the device. As soon as the strands of wire are separated and the wire has travelled say three or four inches away from the face of the device they regain their twisted engagement such action being a necessary requirement when the line is manufactured.

The device may be separated from the pulley holder if so desired, in which case it would be gripped by the hand and slid along the stationary two-strand line to effect the same separation of the strands for the placement or for the release of the clothes. This method however is not as convenient or as practical on account of having to use one hand to manipulate the device on the line while placing the clothes with the other hand.

2

The strands of wire occupying an important position in the manufacture of this device are of specially selected material to withstand the un-twisting and twisting operations, and to return to the twisted formation when required. These strands may be separated within the invented device either in a vertical direction over rollers or in a horizontal direction within the case over the enclosed sheaves, this being a matter of convenience in manufacture, since the results are identical in each case, and the case is so designed as to hold the roller style or the sheave style, whichever type is preferred.

Drawings are attached to this specification on which are to be found the following figures illustrating the device:

Fig. 1 shows an elevational view of the clothes line with supporting end posts and with the device mounted in place, being attached to the holder of one end pulley.

Fig. 2 is a part sectionalized side view of the manipulator.

Fig. 3 is a half section view on the vertical center line of Fig. 2.

Fig. 4 is a part sectionalized side view of a different arrangement of internal parts to maintain the strands of wire separated in a horizontal direction.

Fig. 5 is a half sectionalized view on the vertical center line of Fig. 4.

Fig. 6 is an end view of the attachment member which secures the manipulator to the clothes line sheave holder.

Fig. 7 shows the attachment member between the manipulator and the clothes line sheave holder; and

Fig. 8 is a perspective view of the roller holder. Similar numerals refer to similar parts throughout the several views.

Referring to the drawings the numeral 1 represents a clothes line consisting of two single strands of wire so twisted during manufacture that they will maintain their longitudinal relative overwrap, and at the same time being of such resilient composition that they will return to normal twist following successive temporary separations from one another within short lengths.

Conventional clothes line sheaves 2 and 3 support the said line 1 in the usual manner, and are carried in holders 4 and attached by bolts 5 to posts 6, one of such bolts having a tightening nut 7.

Referring to the modification of the invention illustrated in Figures 2 and 3, the manipulator

or strand separating device A includes a hollow tubular member 8 which is adapted to enclose a portion of the endless clothes line 1 which is extended between the end sheaves 2 and 3. The tubular member 8 is firmly supported by a relatively stiff frame 10 which is secured to the frame 9 of one of the two end sheaves 2 and 3 which carry the endless clothes line 1. The tubular member 8 is formed of rigid material, and can be streamlined for appearance if desired.

A pair of pulleys 11 are rotatably mounted within the tubular member 8, with their axes arranged transversely thereof. The pulleys 11 are inserted into transversely apertured openings 12 formed within an enclosing, partly circular block 13 which forms a spindle and which is rotatable concentrically within and is positioned slightly towards one end of the member 8. The openings 12 can be designed to permit the pulleys to rotate one on the other to reduce friction therebetween. The block member 13 is slotted, as indicated by the numeral 14, diametrically towards the centre thereof at sufficient depth to expose the pulleys, over the surface of each of which a separated wire strand of the line 1 travels as the line is drawn through the tubular member 8. The block or spindle 13 is retained in place in the tubular member by rings 15, one of which is pressed into each end of the tubular member after the block 13 has been inserted therein, the space between the rings forming a raceway for the block. The rings 15 can be secured in place by pins 15a which are extended through aligned openings in the tubular member and the rings. The rollers, being shorter than the openings 12, are secured in place by pins 16.

In the modification of the invention illustrated in Figures 4 and 5, a pair of pulleys 17 are rotatably mounted in axial alignment on an axle or spindle 18 which is disposed in the tubular member 8a at right angles to the long axis thereof. This spindle 18, with its pulleys 17, is rotatable concentrically about the axis of the tubular member 8a with its ends travelling in a circular groove or raceway 18a formed by the space between the opposing surfaces of the rings 30 which are inserted into the tubular member, one at each end thereof. A circular guide block 19 is formed or provided between each pulley and the opposing surfaces of the rings 30 to reduce the friction between the pulleys and the rings and to properly retain the movable parts therein. The rings 30 are secured in place by the pins 30a which are extended through aligned holes in the tubular member and the rings.

A friction washer 21 is mounted on the spindle 18 between the pulleys 17. To further aid in reducing friction between the spindle 18 and the walls of the groove 18a, the opposing faces of the rings 30 are cut back angularly, as indicated by the numeral 22. Also, the spindle 18 is provided with journal caps 23 on each of its ends which are in contact with the knife edges 22 of the opposing faces of the rings 30 as a further means of reducing friction.

The ends of the line 1 can be joined in any convenient manner, such as indicated by the numeral 20 so that strands will retain, and after passing through the spreader or manipulator return to their relative twist along the line.

I claim:

1. In combination in a spreader of the char-

acter described, a tubular member, a ring member permanently fixed to the interior of each open end of the said tubular member and spaced from each other, and located within the said tubular member, a spindle, two pulleys loosely mounted thereon, said ring members and the tubular member forming a raceway receiving the ends of the spindle.

2. A clothes hanging device comprising a clothesline having a pair of twisted strands, and a strand separator mounted thereon, said separator comprising a cylindrical hollow body, an axle having pulleys rotatably mounted thereon and separately engaging said strands, said body having means providing an annular raceway, in a plane perpendicular to the strands, which receives the ends of the axle.

3. In combination in a spreader for separating the strands of a twisted clothes line having two strands, a hollow barrel member, a pair of spaced ring members positioned between the ends of said barrel member, a spindle extending transversely of said barrel member with its ends positioned in the space between the ring members and freely rotatable therein, a pair of pulleys rotatably mounted on said spindle, and means positioned between each of said pulleys and the adjacent end of said spindle for spacing said pulleys on said spindle.

4. In combination in a spreader for separating the strands of a twisted clothes line having two strands, a hollow barrel member, a pair of spaced ring members positioned between the ends of said barrel member, a spindle extending transversely of said barrel member with its ends positioned in the space between the ring members and freely rotatable therein, a pair of pulleys rotatably mounted on said spindle, means positioned between each of said pulleys and the adjacent end of said spindle for spacing said pulleys on said spindle, and means for spacing said pulleys from each other.

5. A clothes hanging device comprising a clothesline having a pair of twisted strands, a strand separator mounted thereon, said separator comprising a cylindrical hollow body, a spindle extending transversely of said hollow body having pulleys rotatably mounted thereon and separately engaging said strands, said body having means providing an annular raceway, in a plane perpendicular to the strands, which receives the ends of said spindle, and means positioned between each of said pulleys and the adjacent end of said spindle for spacing said pulleys on said spindle.
